CLAIM

The ornamental design for a revolving pendulum clock, as shown and described.

DESCRIPTION

FIG. 1 is a front elevational view of a revolving pendulum clock showing my new design;

FIG. 2 is a top plan view thereof;

FIG. 3 is a rear elevational view thereof;

FIG. 4 is a bottom plan view thereof;

FIG. 5 is a left side elevational view thereof, the right side view being a mirror image thereof;

FIG. 6 is a front elevational view thereof with the glass dome raised for better clarity and ease of illustration.
